United States Patent Office

Des. 196,905
Patented Nov. 19, 1963

196,905

PASSENGER-CARRYING VEHICLE

Flake E. Dardenne, 4301 Santa Ana St.,
Huntington Park, Calif.

Filed Mar. 1, 1963, Ser. No. 73,762

Term of patent 14 years

(Cl. D14—3)

FIG. 1 is a perspective view taken from the forward right-hand corner of the vehicle;

FIG. 2 is a perspective view taken from the rear left-hand corner of the vehicle;

FIG. 3 is a horizontal section through the vehicle looking downwardly;

FIG. 4 is a longitudinal vertical section taken substantially upon the line 4—4 upon FIG. 3;

FIG. 5 is a vertical section taken substantially upon the line 5—5 upon FIG. 4 in the direction indicated.

The dominant features of my design reside in the portions shown in full lines.

I claim:

The ornamental design for a passenger-carrying vehicle, as shown and described.
